VACUUM-CLEANER ATTACHMENT FOR AUTOMOBILES

Application filed June 1, 1929. Serial No. 367,817.

The invention has for an object to provide a novel means for utilizing the exhaust gases emitting from an automobile exhaust pipe or muffler for creating a suction that can be put to practical use in vacuum cleaning upholstery in or about the automobile.

In its more detailed nature the invention resides in the provision of a novel suction creating head mountable as an attachment upon the discharge end of an exhaust or muffler tube and comprising a pipe-like body, one end thereof being mountable on the said tube end and the other end being constricted to form a restricted discharge end; a pipe section mounted in the receiving end of the pipe-like body and constricted therein to provide a surrounding enlarged suction chamber and a reduced tubular portion within the enlarged portion which communicates with the exhaust or muffler tube and closes direct communication into said enlargement and which is provided with novel suction creating obstruction openings and extends to a position for delivering into the discharge end of the pipe-like body and for providing a restricted annular passage from the enlarged portion into said discharge end, and a lateral connection communicating with the suction chamber and affording means for connecting a flexible vacuum line which may be equipped with a suitable cleaner nozzle to enable suction cleaning of upholstery.

With these and other objects in view which will more fully appear, the nature of the invention will be more clearly understood by following the description, the appended claims, and the several views illustrated in the accompanying drawings.

In the drawings:

Figure 1 is an elevation illustrating the invention,

Figure 2 is a central longitudinal section, and

Figure 3 is a cross section taken on the line 3—3 on Figure 2.

Like reference numerals designate corresponding parts throughout the several figures of the drawings.

In the drawings, 1 designates the tubular discharge end of the usual exhaust pipe or

muffler. A mounting band 2 is secured upon the member 1 and carries diametrically oppositely disposed radial lugs or projections 3 the purpose of which will become evident as the description progresses.

Our improved device is in the nature of an attachment and comprises a main pipe-like body 4 which is conically constricted as at 5 to provide a reduced discharge end 6.

A second pipe-like body 7 is secured in the receiving end of the body 4 and is conically constricted as at 8 to provide a reduced discharge end 9 which extends to a point adjacent the entrance into the discharge end 6 so as to provide a restricted annular passage 10 and is so positioned in the body 4 as to provide a relatively large surrounding suction chamber 11 communicating with the discharge end 6 through the restricted throat 10.

The joined entrant ends of the bodies 4 and 7 conjointly form a mounting neck which may be equipped with bayonet slots 12 to engage the lugs 3 of the band 2 to provide a convenient removable mounting for the device.

The reduced tube portion 9 is provided with a plurality of suction creating obstruction openings 13 communicating between the interior of said tube and the suction chamber surrounding it. These openings are formed by transversely slitting the tube at the desired intervals and bending the resulting lips 14 nearest the discharge end outwardly and the lips 15 nearest the inlet end inwardly to form obstructions to free passage of the exhaust gases through the tube portion 9.

A tubular extension 16 projects from one wall of the suction chamber and affords means for connecting one end of a flexible tube or line 17 which may carry a suction nozzle (not shown) of suitable design at its free end to enable vacuum cleaning of upholstery in or adjacent the automobile of which the exhaust pipe or muffler forms a part.

In operation, as the exhaust gases rush past the lips 14, 15 and the openings provided thereby, and also past the restricted annular throatway 10, a partial vacuum will be created in the chamber 11 causing air at 100

atmospheric pressure to tend to rush into the lateral tube 16.

The degree of efficiency of the vacuum will of course vary with the speed of the motor emitting the exhaust gases and it will be obvious that attached device may be effectively employed as a vacuum cleaner as outlined above.

It is of course to be understood that the details of structure and arrangements of parts may be variously changed and modified without departing from the spirit and scope of our invention.

We claim:

1. A device of the character described comprising a tubular body having an entrant end and a discharge end and having openings therethrough spaced radially about its body intermediately of its ends, said openings being formed by transversely slitting the body and bending the resulting lips nearest the discharge end outwardly and the resulting lips nearest the entrant end inwardly, a second body surrounding the first mentioned body to form a surrounding vacuum chamber and having an open end extended beyond the discharge end of the first mentioned body, said extended open end being constricted as it passes said discharge end to provide a reduced diameter discharge extension and a restricted annular throatway surrounding said discharge end, and means to removably secure the device upon an exhausting medium.

2. A device of the character described comprising inner and outer tubular bodies forming therebetween a vacuum chamber and having inlet and discharge ends, the outer body having a suction inlet in communication with the vacuum chamber and located between the inlet and discharge ends of the inner body, the inner body being provided with a plurality of openings located between the suction inlet of the outer body and the discharge end of the inner body, lips projecting inwardly from the inner body on the sides of the openings located towards the inlet end of the body to form a restricted passage therein, and lips projecting outwardly from the inner body on the sides of the openings located towards the discharge end of the body, the lips at each opening conjointly forming an inlet passage inclined inwardly towards the discharge end of the inner body.

3. A device of the character described comprising inner and outer tubular bodies forming therebetween a vacuum chamber and having inlet and discharge ends, the outer body having a suction inlet in communication with the vacuum chamber and located between the inlet and discharge ends of the inner body, the inner body being provided with a plurality of openings located between the suction inlet of the outer body and the discharge end of the inner body, lips projecting inwardly

from the inner body on the sides of the openings located towards the inlet end of the body to form a restricted passage therein, and lips projecting outwardly from the inner body on the sides of the openings located towards the discharge end of the body, the lips at each opening conjointly forming an inlet passage inclined inwardly towards the discharge end of the inner body, the outer surfaces of the inwardly projecting lips and the inner surfaces of the outwardly projecting lips being concaved.

4. A device of the character described comprising inner and outer tubular bodies forming therebetween a vacuum chamber and having inlet and discharge ends, the outer body having a suction inlet in communication with the vacuum chamber and located between the inlet and discharge ends of the inner body, the inner body being provided with a series of openings arranged in a plane transverse to the longitudinal axis of the bodies and located between the suction inlet of the outer body and the discharge end of the inner body, lips projecting inwardly from the inner body on the sides of the openings located towards the inlet end of the body to form a restricted passage therein, and lips projecting outwardly from the inner body on the sides of the openings located towards the discharge end of the body, the lips at each opening conjointly forming an inlet passage inclined inwardly towards the discharge end of the inner body.

In testimony whereof we hereunto affix our signatures.

WALTON CLARENCE REHWOLD.
JAMES GORDON DUFF.
